US0D1066922S

(12) **United States Design Patent** (10) **Patent No.:** **US D1,066,922 S**
(45) **Date of Patent:** **** Mar. 18, 2025**

(54) **COSMETIC MIRROR**

(71) Applicant: **Shenzhen Global Electronic Technology Co., Ltd**, Shenzhen (CN)

(72) Inventor: **Defang Chen**, Suzhou (CN)

(73) Assignee: **Shenzhen Global Electronic Technology Co., Ltd**, Shenzhen (CN)

(**) Term: **15 Years**

(21) Appl. No.: **29/905,739**

(22) Filed: **Oct. 25, 2023**

(30) **Foreign Application Priority Data**

Aug. 16, 2023 (CN) 202330522949.8

(51) LOC (15) Cl. **06-07**

(52) U.S. Cl.

USPC **D6/309**; D6/308

(58) **Field of Classification Search**

USPC D6/300, 308, 309; D14/172, 209.1, 211, D14/341; D26/51, 56, 63; D28/64.1–64.7

CPC A45D 42/00; A45D 42/10; A45D 42/16

(57) **CLAIM**

The ornamental design for a cosmetic mirror, as shown and described.

DESCRIPTION

FIG. 1 is a front, right and top perspective view of a cosmetic mirror, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 2 thereof;

FIG. 10 is a rear, left and bottom perspective view of a cosmetic mirror with the rear ring closed;

FIG. 11 is a front, right and top perspective view of a cosmetic mirror in disassembled status thereof; and,

FIG. 12 is an enlarged view of portion 12 of FIG. 10 thereof. The broken lines shown in the drawings illustrate portions of the cosmetic mirror that form no part of the claimed design. The dot-dash broken lines depict the boundaries of the enlargements that form no part of the claimed design.

1 Claim, 12 Drawing Sheets
